UNITED STATES PATENT OFFICE.

BRUNO SCHNEIDER, OF BUCHHOLZ, GERMANY.

MUSIC-LEAF TURNER.

SPECIFICATION forming part of Letters Patent No. 448,265, dated March 17, 1891.

Application filed February 28, 1890. Renewed February 4, 1891. Serial No. 380,128. (No model.)

To all whom it may concern:

Be it known that I, BRUNO SCHNEIDER, a subject of the King of Saxony, residing at Buchholz, Kingdom of Saxony, German Empire, have invented an Improved Music-Leaf Turner, of which the following is a specification.

This invention relates to an improved music-leaf turner which is operated by a pressure of the hand, knee, or foot upon a key or treadle.

The invention consists in the various features of improvement more fully pointed out in the claims.

15 In the accompanying drawings, Figure 1 is a front view of my improved music-leaf turner. Fig. 2 is a front view of the lifting mechanism. Fig. 3 is a side view of the same, and Fig. 4 a perspective view of the upper part 20 of a traveling rod with running sheave.

The letter *a* represents a desk, musical instrument, or support of a music-book. To the upper corners of this desk a rail *c* is secured or removably fitted. This rail extends 25 in a downward-inclined plane from the right to the left and has a slight forwardly-extending curve at its center. The rail *c* may be composed of two sections joined to each other, as at *c**, for the purpose of more conveniently 30 storing the rail when out of use.

d is a lifting-rod, preferably bent at its lower end and provided with a key *e*, that may be reached by the hand, or the lifter may be provided with a treadle or be operated by 35 the knee. On forcing the key *e* down the rod *d* will be lifted against the action of a spring *f*. The rod *d* may also be formed in two sections secured to each other, as at *s*. The rod *d* is guided through a lug *g*, as at *a**, 40 secured to the rear of the desk *a*.

h is a guide-rod supported by a socket of the lug *g*, and thus firmly held in place. The upper end of rod *h* is bent to form an arm *i*, projecting first forward and then upward. It 45 terminates in a pin *h*', which engages the rail *c* to steady the rail in its position. The bent part *i* of rod *h* further carries a pivoted cross-bar *t*, having near each end an upwardly-projecting pin *k* and *l*. The upper part of the 50 lifting-rod *d* extends parallel to the bent arm *i*, as shown. The free end of rod *d* is pivot-

ally connected to one end of the cross-bar *t*, adjacent to the pin *l*.

m are metal rods bent at the upper ends to receive the trunnions of running sheaves 55 *n*, which slide on rail *c*. A bent arm *o*, projecting from rod *m* and passing across the front of sheave *n*, keeps the several rods *m* properly distanced from each other. From the rear of each rod *m* there projects also a 60 pin *p*, that engages the pin *k* of cross-bar *t*. Said pin *k* stops the first traveling rod *m* of the series by extending into the path of pin *p*. By pressing down key *e* the rod *d* will be lifted, as described, the pin *l* will be forced 65 up, while pin *k* will be forced down to clear the pin *p* of the traveling rod *m*. The running sheave *n* of said rod is now free to roll down the inclined rail *c*. The second rod *m*, instead of rolling down together with the 70 first one, is stopped by the raised pin *l*. As soon as the key *e* is released the lifting-rod *d* is returned to its normal position by the spring *f*, the pin *l* is lowered, and the pin *k* is raised. The rod *m* consequently is set free 75 from pin *l*, but is stopped by pin *k*, that engages pin *p*, as before described, until the key is again depressed.

The sheets of music are held in position by a wire *q*, the upper hooked end *r* of which 80 embraces the upper edges of the leaves.

To prevent the traveling rods *m* from striking against the frame at the end of their motion, a movable arm *x* is provided at the lower left-hand corner of the desk, the upper end 85 of which is connected to the frame by a slack cord, as at *w*. This cord will receive the impact from the rods *m*. The loose disk or ring *z*, slipped over the arm *x*, prevents said arm from striking the desk when the traveling 90 rod *m* falls against the cord. In setting the apparatus all the rods *m* are carried up the rail *c*, where they are held in position by the pin *k* of cross-bar *t*, that engages the pin *p* of the foremost rod *m*. The lower ends of rods 95 *m* are slipped between the music-sheets, so that one rod is between every two pages of music. Every descent of the key *e* or lift of the rod *d* sets the foremost traveling rod *m* free to roll down the rail *c*, as described, and 100 the rod being preferably weighted turns the sheet over from the right to the left while

passing down. To prevent the traveling rods from being stopped by the fold of the book, the rail *c* has a curve over said fold. In this way the rods pass clear of the fold of the book while running down the rail.

5 What I claim is—

1. The combination of an inclined rail with a series of rods *m*, having pulleys *n* that engage said rail, and with a lifter *d*, and a stop 10 operated by said lifter and engaging the rods *m*, substantially as specified.

2. The combination of an inclined rail with a series of rods *m*, having pulleys *n* and pins *p*, and with lifter *d*, and pivoted cross-arm *t*, having pins *k l*, substantially as specified. 15

In testimony whereof I sign my name, in the presence of two subscribing witnesses, this 18th day of September, 1889.

BRUNO SCHNEIDER.
